US0D1101743S

(12) **United States Design Patent** (10) **Patent No.:** **US D1,101,743 S**
(45) **Date of Patent:** **** Nov. 11, 2025**

(54) **SELF-SERVICE TERMINAL**

- (71) Applicant: **NCR Voyix Corporation**, Atlanta, GA (US)
- (72) Inventors: **Rafael Yepez**, Duluth, GA (US); **Shelby Apps**, Atlanta, GA (US); **Kimberly Wang**, Sugar Hill, GA (US)
- (73) Assignee: **NCR Voyix Corporation**, Atlanta, GA (US)

(**) Term: **15 Years**

(21) Appl. No.: **29/962,306**

(22) Filed: **Sep. 11, 2024**

(57) **CLAIM**

The ornamental design for a self-service terminal, as shown and described.

DESCRIPTION

FIG. 1 is a perspective view of a self-service terminal showing our design;

FIG. 2 is a left side view of the self-service terminal shown in FIG. 1;

FIG. 3 is a right side view of the self-service terminal shown in FIG. 1;

FIG. 4 is a front view of the self-service terminal shown in FIG. 1;

FIG. 5 is a back view of the self-service terminal shown in FIG. 1; and,

FIG. 6 is a top view of the self-service terminal shown in FIG. 1.

The broken lines represent portions of the self-service terminal that form no part of the claimed design.

1 Claim, 5 Drawing Sheets
